UNITED STATES PATENT OFFICE.

WILLIAM HENRY BAKER, OF MONTREAL, QUEBEC, CANADA.

STOP-MOTION FOR LOOMS.

1,078,406.

Specification of Letters Patent.

Patented Nov. 11, 1913.

Application filed March 10, 1913. Serial No. 753,814.

To all whom it may concern:

Be it known that I, WILLIAM H. BAKER, a citizen of the United States, residing in Montreal, in the Province of Quebec, Canada, have invented certain new and useful Improvements in Stop-Motions for Looms, of which the following is a specification, reference being had to the accompanying drawings, forming part thereof.

10 This invention has reference to improvements in that class of warp stop motions for looms having relatively slideable members one of which is adapted to be actuated during the normal operation of the loom and is adapted to be arrested, at the occurrence of a break or a fault in the warp, by drop devices normally sustained out of arresting engagement with said members and the invention consists in the novel means for 20 supporting said relatively slideable members and for engaging the guide member thereof.

One object of the invention is to improve the construction of the guide supporting and holding device.

25 Another object of the invention is to so construct a bridge piece, for the guide members, having a rod engaging collar that the warp threads cannot be caught between said collar and the bridge and broken.

30 Other objects of the invention will appear from the following description.

The invention consists in the novel construction of the support for the guide bar or member.

35 The invention also consists in the novel construction of the bridge.

The invention still further consists in such other novel features of construction and combination of parts as shall herein- 40 after be more fully described and pointed out in the claims.

Figure 1, represents a view in elevation of parts of a warp stop motion illustrating this invention removed from a loom, portions 45 of the same being shown in section. Fig. 2, represents a side view, on enlarged scale, of one of the guide bar supports, showing one of the slide bars engaged therewith.

50 Fig. 3, represents a plan view of the same. Fig. 4, represents a sectional view taken on line 4—4 Fig. 1.

Similar characters of reference designate corresponding parts throughout.

As shown in the drawings in its preferred 55 form 5 indicates a portion of one of the

members or angle rods adapted to sustain the warp stop motion in position in a loom. This rod 5 receives the bore of the stirrup member 6 which has the extension 7 furnished with the stud 8 on which the solid 60 vibrator 9 is mounted to swing. The stirrup member 6 is preferably made of cast metal and has a depending arm furnished with the horizontal stirrup bar 10 having the guide bar seats 11, 11 formed therein.

In order to hold the ends of the guide bars from longitudinal movement in said seats I provide the stirrup bar 10 with the steel holder strip or bar 12 which extends across the open sides of the seats 10, 10 and has the 70 inturned ends 13, 13 which, in the casting of bar 10, are included in the body of said bar. In order to prevent the lifting of the ends of the guide bars from said seats 11, 11 I provide the bar 10 with the keeper 14 which bears at its lower end against the side of bar 10 and at its upper end extends over the open upper ends of said seats 11, 11.

This keeper is supported in place by the spring 15 which is carried on screw 16, secured in bar 10, which spring bears against the keeper as shown in Fig. 1 of the drawings.

Supported by the stirrup bars as 10 are the guide bars 17, 17 which have longitudinal grooves in their upper edges, which edges are serrated or have the teeth 18, 18, and the lower edges of said guide bars near their ends have the notches 19, 19 which are engaged with the holder strip 12 while the 80 ends of said guide bars 17, 17 are received by the seats 11, 11 of bar 10. Adjacent the ends of said guide bars are slots as 20, through which the pins as 21 of the slide bars 22, 22 extend. These slide bars or 85 strips 22, 22 have the teeth 23, 23 in their upper edges and are slideable in the grooves in the upper edges of bars 17, 17 during the normal operation of the loom. The provision for vibrating or actuating said slide bars 22, 22 is the vibrator 9 which is pivotally mounted on the stud 8 of member 5 and has the depending arm 25 having the lateral extension 26 which is furnished with a series of upwardly extending fingers 27, 27 90 having transverse grooves 28, 28 in which the pins 21, 21 of the several slide bars 22, 22 are engaged. The vibrator 9 is operated in any manner now well known in

100 this art from some movable part of the loom 105 110

mechanism as, for instance, shown in Letters Patent of the United States, No. 1,026,941, granted to me May 21, 1912.

Provision is made for bracing the guide bars 17, 17 at a point intermediate the length of said bars, such provision comprises the center brace or bridge 29 which is formed of compressed fibrous non-abrasive material. This center brace has the vertical slots 30, 30 to receive the guide bars 17, 17 and is pivotally mounted at one edge to swing on the usual warp support rod 31 while at the other edge said brace or bridge 29 has the hook 32 to engage the other, usual warp support rod 33. Said center brace is supported, during the operation of the loom, by the collar 34 which has the offset arm 35, fastened to said brace 29, and the set screw 36 extending through the wall of said collar to engage with the periphery of said warp support rod 31. Extending through a slot in said center brace 29 is the brace rod 37 which may swing downward with the center brace.

By the use of the offset arm 35, collar 34 is spaced from the center brace 29 sufficiently that one or more warp threads may rest on or move over the rod 31 without catching between said collar 34 and said bridge or brace 29 and in hereafter referring to said collar as spaced from said bridge or brace I mean to define a space sufficiently large to freely accommodate one or more warp threads. By making the center brace or bridge 29 of indurated fiber I find that the members 17 and the warp threads passing adjacent thereto are subjected to less wear than if said brace or bridge was of metal.

Having thus described my invention I claim as new and desire to secure by Letters Patent.

1. A stop motion of the nature described comprising a supporting bar having a series of parallel seats and a holding bar extending transversely across the side openings of said seats, a series of guide bars seated in said seats and having notches engaged with said holding bar, and a keeper hingedly mounted on said supporting bar and adapted to hold said guide bars in engagement with said holding bar.

2. A stop motion of the nature described comprising a supporting bar having a series of parallel seats and a holding bar extending transversely across the side openings of said seats, and a series of guide bars seated in said seats and having notches engaged with said holding bar.

3. A stop motion of the nature described

comprising a supporting bar formed of cast metal and having a series of seats and having a holding bar or strip of steel having in-turned ends cast into the body of said supporting bar, and a series of guide bars seated in the seats of said supporting bar and engaged with said holding bar.

4. A stop motion of the nature described comprising a series of guide bars, a warp support rod, and a two piece center brace for said guide bars pivotally mounted on said warp support rod.

5. A stop motion of the nature described comprising a series of guide bars, a warp support rod, a brace for said guide bars pivotally mounted on said rod, and a collar mounted on said arm and having an offset arm secured to said brace whereby said collar is spaced from said brace.

6. A stop motion of the nature described comprising a series of guide bars, a warp support rod, a brace for said guide bars having slots to receive said bars, a collar embracing said rod and having an offset arm secured to said brace, and a set screw in said collar for engaging said rod.

7. A stop motion of the nature described comprising a pair of warp support rods, a series of guide bars parallel with said rods, a fibrous brace for said guide bars having a metallic collar pivotally mounted on one of said warp support rods and having a hook for engaging the other of said warp support rods, and means for securing said brace from movement.

8. A stop motion of the nature described comprising a pair of warp support rods, a series of guide bars, a brace for said guide bars formed of indurated fiber pivotally mounted on one of said rods and having an extension for engaging the other of said rods, said brace having a series of spaced slots in which said guide bars are seated.

9. A stop motion of the nature described comprising a series of guide bars, a warp support rod, a non-metallic brace for said guide bars, a metal collar mounted on said warp support and having an offset arm secured to said brace whereby warp threads may freely move on said rod between said collar and said brace, and means carried by said collar for engaging said rod to prevent the rotation of said collar.
